UNITED STATES PATENT OFFICE.

WILLIAM S. LACKEY, OF CAMDEN, NEW JERSEY.

TRANSPARENT, FOLDING, RAIN-PROOF WINDOW SCREEN.

Application filed July 12, 1927. Serial No. 205,119.

My present invention relates to transparent, folding, rain-proof window screens and the principal object of the invention is to provide a window screen of the type described which can be used inside the usual window sash, and which when folded and in position will not interfere with the raising and lowering of the sash, and which when the sash is raised and the screen opened, will perform all the functions of an ordinary window screen and in addition exclude the weather such as rain or snow without obstructing the view from the window or interfering with ventilation.

To this end my invention contemplates a major frame of a height not greater than one-half the height of a window sash. The side edges of this frame are grooved to receive tongued members or keepers adapted to be secured to the inside of the window frame and next to the lower sash. By varying the lateral extent of the keepers, the frame may be made to fit any size window, the frame remaining standard. On the inside of this frame at each side thereof, I provide triangular side wings, pivoted on perpendicular pins at top and bottom thereof, so that they cannot be swung outwardly beyond a plane at right angles to the plane of the main frame. These wings carry glass.

To the top of the main frame is secured a supplemental frame as by hinges, which frame likewise carries glass, and is adapted to rest upon the hypotenuse of the triangular wings, and make a joint therewith. To the bottom of this frame is hinged a screen carrying frame, adapted to occupy a horizontal position, its short side edges lying inside the side wings, its unattached longitudinal edge overlying and engaging the main frame.

The various parts are so proportioned that the whole may be folded so as to be included between two planes including the front and rear faces of the main frame.

The invention further consists in the novel arrangement, construction and combination of parts herein shown and described.

In the embodiment illustrated:

Fig. 1 is a front view of the device folded and the window sash lowered.

Fig. 2 is a front view of the device unfolded and the window sash raised.

Fig. 3 is a side view partly in section

showing two of the devices used in a window, one resting on the other.

Fig. 4 is a view similar to that of Fig. 3 showing the device used in the top window sash.

Fig. 5 is a fragmental sectional view showing the device folded.

Fig. 6 is a fragmental sectional view showing the method of hinging.

Fig. 7 is a detail partly in section showing the hinge pins.

Fig. 8 is a further detail.

Referring with particularity to the drawings, I have shown at 1 a main frame of wood or other desirable material of substantially rectangular shape of a height not more than one-half the height of a window sash. The reason for this is that it may be desirable to use two of the devices in a single window sash as shown in Fig. 3.

The lateral edges of the frame are grooved as at 2 in order to receive the tongues of the keeper element 3 which is secured to the window frame 4 and next the window sash 5. It is desirable that the keeper 3 extend up the entire height of the window frame, so that the device may be used at any level. Stops 6 are provided to hold or retain the device at any position on the keepers.

Countersunk into the main frame 1 are bearing blocks 7 which receive the hinge pins 8 of side wings 9. Similar provision is made for pins at the bottom of the side wings.

These wings are preferably of triangular shape, the longer leg adjacent the right angle lying next the frame 1. Obviously, the wings 9 may be made of any desirable material, but I have found it convenient to construct the same of sheet material such as aluminum. In this form the wings proper consist of three equal thicknesses of metal, riveted together, the center thickness being of less lateral extent than its neighbors. A piece of glass conforming to the wing shape and of a thickness equal to that of the wing frame is held between the two outside metal strips.

The short leg or base of the wings 9 is provided with a downwardly projecting extension 10 which serves a purpose to be described later. It will be noted that the hinge pins of the side wings are located very near the inside edge of the main frame 1, so that when the wings are swung outward to the open position, they will not go beyond a plane at

right angles to the face of the main frame.

To the top of the main frame 1 and at the outer edge thereof, I hinge a window consisting of a skeleton framework 11 made substantially as in the case of the triangular side wings, except that this framework 11 is of rectangular shape. The hinges are shown at 12 countersunk into the main frame 1. The vertical portions of the framework 11 of the front window are provided with angular flanges 13 which when in opened out position engage the outside of the side wings. This effectively prevents swinging out of the wings beyond the point desired and at the same time makes a water-tight and insect-tight joint between the parts.

To the bottom of the front window 11, I hinge a bottom 14 carrying a screen 15. The inner longitudinal portion of the bottom is provided with a flange 16 which overlies the bottom longitudinal of the main frame 1 and secures the parts in this position. It is to be noted that the over-all length of the screen bottom is less than the over-all length of the front window 11 and fits snugly between the opened out side wings. The vertical components of the front window framework 11 lie along the hypotenusal edge of the side wings.

As above described, it will be seen that a transparent, folding, weather-proof window screen has been provided, which is also insect-proof in that all its joints are snugly fitting. At the same time the device neither obstructs the view from the window or interferes with ventilation.

I have found it desirable to provide a front plate 17 set into the bottom of the main frame 1 which will carry the bottom hinge pins of the side wings. This plate is perforated as at 18, which apertures are covered with screening 19. This provides a lesser degree of ventilation for the window than when the device is opened out and in some instances is most desirable.

In order to fold the device, the flange 16 of the screened bottom 14 is raised and pushed out. This lifts the front window 11 from the side wings and permits the side wings to be swung inwardly about their pivot pins to a point so that the downwardly projecting extension 10 engages the plate 17. The thicknesses of plate 17 and the wing frames are so proportioned that when the extension 10 engages the plate, the plane of the wing will substantially coincide with the plane of the plate and main frame.

The above operation having been completed, the screened bottom 14 is swung upwardly against the front window 11 and the latter pulled in toward the main frame. A spring catch 20 at the bottom of the main frame, secures the front window so that its outside plane substantially coincides with the outside plane of the main frame. The

screened bottom 14 lies between the side wings and the front window, the flange 16 of the screened bottom being cut away at the extremities of the bottom in order to clear the side wings.

As folded, the entire device is contained within the front and back planes of the main frame so that there are no projecting parts to be injured, or to get in the way.

To unfold or open out the device, the spring button 21 at the bottom of the main frame is pushed which disengages the front window from its spring catch 20. The front window and screened bottom are pushed outwardly far enough for the side wings to be swung out. The front window is now lowered into engagement with the hypotenuse of the side wings, the flanges 13 overlying the outside of the wing. The screened bottom is now dropped into place, its flange 16 overlying the plate 17 and the whole is secured.

In using the device it will be apparent that many useful combinations may be made. For instance, if only a single one is to be used it may occupy the lower half of the lower sash or upper half of the upper sash. If the upper location is desired, the device may be held in this position by means of the appropriate stop 6.

Where it is desired to completely raise the lower window frame, two of the devices may be made use of, one resting on top of the other (see Fig. 3).

In all cases, it will be noted that when the device is folded, the window frame may be raised or lowered without interference.

The parts are so proportioned that when in opened out position, no part of the device will project beyond the outer building wall line.

What is claimed is:

1. A folding window screen comprising a main frame, triangular side wings vertically hinged thereto at each side thereof, a front window hinged at the top thereof, said window carrying a hinged and screened bottom, engageable with and resting on the main frame and between the side wings.

2. A folding window screen comprising a main frame, triangular side wings vertically hinged thereto at each side thereof, the plane of the side wings being substantially at right angles to the plane of the main frame, a front window hinged to the top of the main frame and resting upon the hypotenuse of each side wing, and a screened horizontal bottom hinged to the bottom of the front window and lying between the side wings.

3. A folding window screen comprising a main frame, triangular side wings vertically hinged thereto at each side thereof, the plane of the side wings being substantially at right angles to the plane of the main frame, a front window hinged to the top of the main

frame and resting upon the hypotenuse of each side wing, and a screened horizontal bottom hinged to the bottom of the front window and lying between the side wings, said front window having angular flanges at its lateral edges engaging the outside of the side wings.

4. A folded window screen comprising a main frame, side wings vertically hinged thereto, a front window horizontally hinged thereto, a screened bottom horizontally

hinged to the bottom of the front window, the bottom lying between the front window and the side wings, the outer plane of the front window being substantially flush with the outer plane of the main frame, the inner plane of the side wings being substantially flush with the inner plane of the main frame. 15

In testimony whereof, I affix my signature.

WILLIAM S. LACKEY.
